United States Patent Office

Des. 208,865
Patented Oct. 10, 1967

208,865

TABERNACLE

William R. Palmer, Jr., 290 Red Fox Road,
Stamford, Conn. 06903

Filed Mar. 26, 1965, Ser. No. 84,452

Term of patent 14 years

(Cl. D29—23)

FIG. 1

FIGURE 4 is a rear view of my tabernacle as shown in FIGURES 2 and 3; and

I claim:

The ornamental design for a tabernacle, substantially as shown and described.
